CURTAIN FIXTURE STRUCTURE

Joseph Schunk, Newark, N. J., assignor to The National Lock Washer Company, Newark, N. J., a corporation of New Jersey

Application June 4, 1936, Serial No. 83,506

3 Claims. (Cl. 156—26)

The present invention relates to a curtain fixture structure, and particularly to the sliding head of the raising and lowering fixture of curtains, such as are used in railroad passenger cars, busses, and the like. The raising and lowering fixture is mounted at the lower end of the curtain and is provided at each end with a head which operates in a metal channel at each side of the window opening. As heretofore constructed these heads were provided with rollers and metal sides, and from the movement and vibration of the car the head would hit the side of the groove producing a very noticeable and objectionable noise. It is an object of the present invention to provide a head which will be noiseless, and to this end it is proposed to provide the head with rubber shoes at each end, which will come in contact with the sides of the grooves when there is sufficient movement or vibration to rotate or slide the fixture in either direction, thereby eliminating any noise that might otherwise be produced through contact of the head with the channel wall.

A further object is to provide a head which will slide easily in the groove, and will operate noiselessly during the raising and lowering of the curtain, due to the fact that metal to metal contact is eliminated and there are no movable parts, such as the rollers of the previous constructions, the bearings of which were apt to squeak if not frequently oiled.

Another object is to provide a retaining and releasing cam having a rubber facing for engaging the guide grooves, preventing marring or scratching of the groove and preventing noise that would result from metal to metal contact.

With the above and other objects in view an embodiment of the invention is shown in the accompanying drawing, and these embodiments will be hereinafter more fully described with reference thereto, and the invention will be finally pointed out in the claims.

In the drawing:

Fig. 1 is a front elevation of the lower end of a curtain, with portions broken away, showing the fixture according to the invention, one end of the fixture being partially shown in vertical section.

Fig. 2 is a front elevation of the head, as used at one end of the fixture.

Fig. 3 is an end elevation thereof.

Fig. 4 is a top plan view.

Fig. 5 is a vertical sectional view taken along the line 5—5 of Fig. 2.

Fig. 6 is a horizontal sectional view, taken along the line 6—6 of Fig. 2.

Fig. 7 is a side elevation of one of the shoe members.

Fig. 8 is a rear elevation thereof.

Fig. 9 is a bottom plan view.

Fig. 10 is a side elevation of one of the metal inserts of the shoe.

Similar reference characters indicate corresponding parts throughout the several figures of the drawing.

Referring to the drawing, the curtain 10 has secured in its lower end, by means of a stitched hem portion 11, a fixture consisting of a tubular rod 12 upon each end of which a head according to the invention is screwed, these heads being engaged and operable in metal channels 13—13 at the respective vertical sides of the window casing. A plate 14 is secured centrally of the rod 12 by a screw 14^a and is provided with a pair of slots 15—15 in which the finger grip portion 16—16 of the locking cam operating rods 17 are engaged, these rods being normally pressed outwardly by means of a spring 18 mounted upon each of them between a washer 19 secured in the tubular rod 12, and through which the rods move slidably, and a washer 20 secured upon the rod 17.

Inasmuch as the heads at each end are of identical construction, except that they are reversed with respect to each other, only one will be described in detail. This consists of a sheet metal frame member 21 of U-shape in horizontal section and having a tubular socket portion 22 secured centrally to the inner side thereof, the end of the tubular member 22 being contracted as at 23 to engage within an opening 24 in the frame member, and being secured thereto by brazing or other suitable means. The socket member 22 is interiorly threaded and as above pointed out is screwed upon at the end of the tubular bar 12. A locking cam member, consisting of a metal insert member 25 and a rubber facing 25^a molded thereon, is mounted between the sides of the frame 21 upon a pin 26, and is normally pressed outwardly by the engagement therewith of the bent end 27 of the rod 17, being thus tightly pressed against the base of the channel 13 to retain the curtain. By pressing the finger grip portions 16—16 toward each other the rods 17 are retracted to release the cam members whereupon the curtain may be raised or lowered as desired.

The frame member is provided at its upper and lower ends with pairs of inwardly offset

ears 28-28, the inward offset being along diagonally disposed bends 29-29, shoulders 30 and 31 being formed at the outer and inner edges of the frame member at the ends of these bends. 5 The bends 29-29 converge toward the outer edges of the frame member, so that the outer edges of the ears 28 are considerably longer than the inner edges.

The shoe members which are mounted at the 10 upper and lower ends of the head upon the ears 28-28 each consist of a resilient U-shaped rubber member 32, one leg of which is longer than the other so that the ends of the legs will engage the shoulders 30 and 31 while the shoe engages about the edges of the ears 28-28, the rubber member being mounted upon an insert member 15 consisting of a pair of metal plates 33-33 having outwardly bent flanges 34-34, which are embedded in the rubber and serve to lock the rubber to the insert member and having diagonal lower edges. The insert member is centrally of the central plane of the shoe and is engaged between the ears 28-28, being secured thereto by means of a pin 35 extending through apertures 20 36-36 in the ears and apertures 37-37 in the plates 33.

The rubber shoes project with respect to outer edges of the frame 21, so that the outer surfaces of the shoe will engage the base of the channel 30 13 as the fixture is raised and lowered therein. The greater length of the outer legs of the shoes provides greater surface contact of the rubber against the base of the channel without increasing the height of the fixture. The side surfaces 35 of the rubber shoes are projected with respect to the ears 28, so that cushioning areas are provided at the upper and lower ends of the frame 21. It will be observed that any tendency of the fixture to turn in the channel or to vibrate will 40 cause the cushion sides of the rubber shoes to engage the sides of the channel, eliminating all noise.

I have illustrated and described a preferred and satisfactory embodiment of the invention,

but it will be obvious that changes may be made therein, within the spirit and scope thereof, as defined in the appended claims.

Having thus described my invention what I claim and desire to secure by Letters Patent is:— 5

1. A curtain fixture head for engaging the side channel of a window casing, comprising a frame having a pair of spaced ears at each end, and a pair of cushion shoes, one at each end, each comprising a metal insert member secured between 10 said ears and a rubber member carried by said insert member surrounding the peripheries of said ears.

2. A curtain fixture head for engaging the side channel of a window casing, comprising a 15 frame having a pair of spaced ears at each end, and a pair of cushion shoes, one at each end, each comprising a metal insert member secured between said ears and a rubber member carried by said insert member surrounding the peripheries of 20 said ears and projecting with respect to the side surfaces of said ears.

3. In combination, a tube, a curtain fixture head rigidly connected to said tube for engaging the side channel of a window casing, said head comprising a frame having a pair of spaced sides forming an opening in the outer side of the frame, a gripping member disposed between said sides and projecting through said open side to contact the channel base, spring means within 30 said tube normally pressing said gripping member outwardly to engage it with the channel base and to retain said frame out of contact with the channel base, a pair of rubber shoes, each projecting with respect to the edges of the open side 35 of said frame to contact the base of the channel at each end of said open side upon tilting about the point of contact of said gripping member with the channel base in the direction of the channel base and having exposed sides upon tilting about the point of contact of said gripping member with the channel base in the direction of the channel sides. 40

JOSEPH SCHUNK.
